Des. 201,450
Patented June 22, 1965

201,450

TURTLE RACEWAY

George J. Gould, 791 Meacham Ave., Elmont, N.Y.

Filed Nov. 25, 1964, Ser. No. 82,791

Term of patent 3½ years

(Cl. D34—15)

FIG. 4

FIG. 5

FIG. 1 is a top plan view of a turtle raceway, showing my design;

FIG. 2 is a side elevational view;

FIG. 3 is a rear end elevational view;

FIG. 4 is a bottom plan view; and

FIG. 5 is a sectional view taken on the line 5—5 of FIG. 1.

I claim:

The ornamental design for a turtle raceway, as shown.
